(57) CLAIM

The ornamental design for a bed, as shown and described.

DESCRIPTION

This application is a co-pending application of one filed with the U.S. Patent and Trademark Office contemporaneously herewith, Ser. No. 29/150,424. A copy of the drawings for that application are attached hereto for easy reference.

FIG. 1 is a perspective view of our new bed design,

FIG. 2 is a top view of our new bed design,

FIG. 3 is a front elevational view of our new bed design,

FIG. 4 is a right side elevational view of our new bed design, which is a mirror image of the left side elevational view; and,

FIG. 5 is a rear elevational view of our new bed design.

The broken lines in the drawing figures are for illustrative purposes only and form no part of the claimed design.
